UNITED STATES PATENT OFFICE.

WILLIAM J. LOURY, OF PITTSBURGH, PENNSYLVANIA.

CARBURETER-SUPPORT.

1,234,482.

Specification of Letters Patent. Patented July 24, 1917.

Application filed November 4, 1915. Serial No. 59,545.

To all whom it may concern:

Be it known that I, WILLIAM J. LOURY, a citizen of the United States, and resident of Pittsburgh, in the county of Allegheny and State of Pennsylvania, have invented certain new and useful Improvements in Carbureter-Supports, of which the following is a specification.

The object of this invention is to provide improved means for supporting the carbureter of an automobile or boat engine, whereby the carbureter is unaffected by the constantly changing position of the vehicle due to grades, slope and roughness of roadway, ruts, etc. As is well known, a carbureter involves more or less delicate adjustments, in connection with all of which a certain position of the carbureter is presupposed for maximum efficiency. For instance, the float which controls the gasoline inlet concededly should be maintained in horizontal position if efficiency detracting influences are to be avoided. Normal operation cannot be had when the carbureter is tilted or inclined. Abnormal positions thereof result in irregular working, being frequently the cause of flooding the engine cylinders with gasoline, increasing the consumption to a wasteful amount, and washing the lubricant from the cylinders, pistons and packing and causing the parts to wear unduly and decreasing the power, also promoting the accumulation of carbon. Or, with the carbureter out of correct position, the gasoline may feed too slowly. Again, with the vehicle standing on a sloping roadway the resulting inclination of the carbureter permits the gasoline to escape and be entirely wasted.

Distorting positions are particularly present in automobile engines. If climbing or descending a steep hill, the whole mechanism, including the carbureter, is necessarily maintained at a corresponding inclination and is at once reflected in the uneven action of the carbureter. And of course the same is true of side slopes in the roadway as well as rough or rutty roadways, each and every deflection of the vehicle from its normal level position disturbing the equilibrium of the carbureter.

Appreciating the difficulties referred to and with a view to securing more uniform action from carbureters of road and water vehicles, I have provided a flexible suspending means for the carbureter whereby its entire weight is supported from above. In

the present adaptation the flexible suspending means is embodied in a universal joint which affords the support lateral movement in any direction without disturbing the carbureter. With the latter balanced on its flexible supporting means in such manner as to maintain it in its most efficient normal position, it will retain such position, the flexible connection compensating for and taking up movements of the support resulting from inclining, jolting or otherwise moving the vehicle out of normal position.

In the accompanying drawings, Figure 1 is an elevation partly in section of a carbureter equipped with the jointed support of the present invention. Fig. 2 is a vertical section of a joint of modified form.

Referring to the drawings, 2 designates the body of the carbureter having its outlet at 3. 4 designates the inlet end of a vehicle engine manifold, and interposed between the latter and carbureter outlet 3 is the flexible suspending means which in the embodiment of Fig. 1 is in the form of a spherical ball joint 5 from which the carbureter in its entirety is suspended and by means of which it is supported. The outer shell of the joint is formed in two parts threaded together at 5', by means of which the joint may be tightened or loosened as desired. The engine inlet throttle 6 may be arranged in manifold 4, as here shown, or in any preferred way.

The employment of a flexible suspending means presupposes such arrangement and adjustment of the carbureter that all parts are in their most efficient position when the carbureter as a whole hangs freely suspended. In the form of carbureter here shown, it is presumed that a correct balance is had when the carbureter is suspended at its outlet 3, in such position the float chamber 7 and float 8 being horizontal. And similarly, the normal position of each and all of the other moving parts is maintained. If the carbureter is not sufficiently heavy to hold it substantially fixed in its suspended position, it may be counterweighted at its lower end as indicated at 9, the counterweight being simply secured to the bottom of the carbureter in such position as to maintain the stability of the suspended carbureter in vertical or upright position. The weighting of the carbureter on one side or the other as may be necessary to reach and maintain the normal position is

of course an obvious expedient if the carbureter in and of itself does not afford the desired balance.

Instead of the spherical joint 5, Fig. 1, the 5 manifold 4 may be connected to the carbureter by the vertical link 10 and the oppositely disposed cross pins 11 and 12 here shown located, respectively, in the manifold and in the carbureter outlet and to 10 which the opposite ends of link 10 are connected, as in Fig. 2. This form of joint affords movement in every direction so that the stability of the carbureter is assured regardless of varying changes in the position 15 or level of the vehicle as a whole. Also, in the modification an inclosing casing 13 of canvas or rubber is provided for maintaining the joint air and gas tight. The gasoline may be fed to the carbureter through 20 a flexible hose 14, and similarly any other necessary connections are flexible, so that the position of the carbureter is not disturbed by relative movement of the vehicle.

It will be understood that the invention 25 may be embodied in or applied to various types of carbureters, and may be advantageously utilized wherever the engine is so movably mounted or carried as to transmit 30 distorting movements to the carbureter.

I claim:

1. The combination of a carbureter support, a carbureter unit suspended therefrom and wholly sustained thereby, said unit including the air inlet, and a universal joint

included in the carbureter unit suspending 35 means whereby the carbureter will remain in normal position regardless of changes in position of the supporting means.

2. The combination of an engine intake manifold, a carbureter unit having its outlet 40 connected to the manifold and suspended therefrom and wholly supported thereby, and a hollow universal joint interposed between the manifold and the carbureter unit for affording the manifold lateral movement 45 in any direction without disturbing the carbureter in its normal suspended position.

3. The combination of a carbureter support, a carbureter unit including the air 50 inlet, a universal joint interposed between the support and carbureter unit with the latter suspended from the joint and wholly supported thereby, whereby the carbureter is maintained in normal position regardless of changes in the position of the support, 55 and a counterweight for the carbureter.

4. The combination with the intake of a vehicle engine, of a carbureter unit including the air inlet, and a universal joint interposed between the intake and carbureter 60 unit and comprising a support for the latter.

In testimony whereof I affix my signature in presence of two witnesses.

WILLIAM J. LOURY.

Witnesses:

J. M. NESBIT,
ELLA McCONNELL.

It is hereby certified that in Letters Patent No. 1,234,482, granted July 24 1917, upon the application of William J. Loury, of Pittsburgh, Pennsylvania, for an improvement in "Carbureter-Supports," an error appears in the printed specification requiring correction as follows: Page 2, after line 42, claim 2, insert the words *said unit including the air inlet*; and that the said Letters Patent should be read with this correction therein that the same may conform to the record of the case in the Patent Office.

Signed and sealed this 18th day of September, A. D., 1917.
